UNITED STATES PATENT OFFICE.

NICHOLAS P. PERKINS, OF PRINCETON, WEST VIRGINIA.

SCROLL-FORMING MACHINE.

1,413,609.

Specification of Letters Patent. Patented Apr. 25, 1922.

Application filed October 11, 1919. Serial No. 330,047.

To all whom it may concern:

Be it known that I, NICHOLAS P. PERKINS, a citizen of the United States, residing at Princeton, in the county of Mercer, State 5 of West Virginia, have invented certain new and useful Improvements in Scroll-Forming Machines; and I do hereby declare the following to be a full, clear, and exact description of the invention, such as will enable others skilled in the art to which it 10 appertains to make and use the same.

This invention relates to wood working machinery and particularly to a machine for forming the scroll of the head of a violin, or kindred musical instrument.

In the manufacture of violins, it is common practice to carve the neck and head by hand, a very laborious as well as expensive operation and it is the object of the present 20 invention to provide a machine with which the scroll may be quickly and economically cut on the prepared blank, with its opposite sides exact duplicates in reverse, while the curve of the spiral at each side of 25 the scroll will have all of the peculiar departures from a perfect spiral, that constitutes the accepted specific shape of this member of the violin, in the art.

Other objects and advantages of the invention will be developed and apparent in 30 the following description.

In the drawings:

Figure 1 is a front elevation of a machine embodying the present invention and illustrating the arrangement and operation of the cutters, the arrangement of the work tables and the means for raising and lowering them with respect to the cutters, together with the means for manually feeding 35 the work radially of the spiral while actuating the cam controlled mechanism that reciprocates the work axially of the spiral to give the peculiar rise and fall to its curve.

Figure 2 is an elevation, showing the right hand side of the machine.

Figure 3 is a section taken horizontally through the central standard of the machine on the line 3—3 of Figure 1, the work 50 carrying table being indicated in dotted lines while the mounting and means for shifting it inwardly and outwardly at right angles to the axis of the scroll, together with the work and the work clamp, are illustrated in top plan view.

Figure 4 is a detail perspective view,

showing disassembled, the vertically and horizontally shiftable carrier members.

Figure 5 is a perspective view of the cam that determines the rise and fall of the work, with respect to the cutter, there being associated with the cam in the drawing, a perspective view of the violin head positioned to correspond with the controlling curvature of the cam.

Figure 6 is an enlarged detail view, partly in section and partly in elevation, showing the manner of mounting the rods with respect to the standard or post of the machine, that raise and lower the abutments 70 for the cams and therewith raise and lower the work tables and the work with respect to the cutters in the initiation of operation of the machine, by depression of the foot 75 pedals.

Referring now to the drawings, the present machine comprises front and rear standards 10 and 11, connected at their upper ends by the transverse member 12 and at points therebelow by a further transverse member 13, it of course being understood 80 that these standards may be braced and formed as desired, they being provided at their lower ends with bases 14 and 15 respectively, that are anchored in the usual 85 manner.

Extending laterally from the upper end portion of the standard 10, are the arms 16 and 17 having terminal bearings in which are received the cutter shafts 18 and 19 provided each with a chuck 20 designed to hold a cutter 21. These cutters are duplicates, having longitudinally extending peripheral cutting blades and having also end cutting blades that extend radially of them, so that 95 when rotated, these cutters will operate both laterally and endwise, the work, as herein-after explained being fed both vertically and laterally to each cutter, while the latter is held against bodily displacement.

The cutter shafts may be driven in any desired manner but are illustrated as provided with belt pulleys 22 with which is engaged an endless belt 23. Upon the standard 10 is an idler 24 against which the belt travels 105 between the pulley wheels at one side of the latter, the sides of the belt at the opposite sides of the pulley wheel 22 being tapered rearwardly of the machine with a twist and then taken downwardly over direction 110 pulleys 25, the pulleys 25 having the inner end portions of their shafts 26 turned down.

wardly and slidably and pivotally engaged in brackets 27' that project from opposite sides of the rear standard 11, these down turned end portions being held normally 5 against movement by set screws 28' respectively. There is thus provided means for properly positioning the pulleys 25. Mounted in suitable bearings in the lower end portions of the standards is a shaft 26, fixed 10 to which is a belt pulley 27 with which the belt 23 engages and through the medium of which it is actuated. Upon the shaft 26 are also the conventional fixed and loose pulleys 28 and 29 respectively, from one to the other 15 of which may be shifted the drive belt 30 through the medium of a conventional belt shift that includes the reciprocating rod 31 having the fingers 32 at one end that embrace the belt while its opposite end is coupled 20 to a shift member 33 that is pivoted upon the base 14. To provide a tightener for the belt 23, the idler 24 is mounted at the end of an arm 26' that is passed slidably through the head of the standard 10 and held normally 25 fixed by the hand screw 27'. The rod terminates at its forward end in a handle 28' for reciprocating it when released from the hand screw.

With the cutters rotated and held against 30 bodily displacement, the blank that has been previously sawed, is raised to a cutter so that the latter may begin its operation at the center of one end of the ultimate scroll. The work is then gradually rotated about the 35 axis of the ultimate scroll while being gradually drawn to shift the said axis horizontally away from the vertical axis of the vertical cutter. The work is at the same time raised and lowered at various speeds, to correspondingly 40 modify the pitch of the scroll.

There will first be described the table upon 45 which the work is clamped, then the means by which the table is raised to present the work to the cutter, then the means through which the table is drawn with its axis in a direction at right angles to that of the cutter then the means by which the table is shifted vertically with a reciprocating movement to effect the pitch, and finally the 50 means for rotating the table.

As hereinbefore stated, there are a pair 55 of cutters 21 employed. In practice, the blank is presented to one cutter for the formation of one scroll end and is then reversed and presented to the other cutter for the formation of the opposite scroll end. There is an attendant to each cutter and the work is passed from one to the other in the completion of both scroll ends. The work carrying 60 and feeding mechanisms for the two cutters, are the same in construction excepting that the screws that feed the work at right angles to the axes of the cutters, have opposite pitches so that when the direction of the 65 rotation of the work is reversed under the

second cutter, it will yet be fed horizontally in the proper direction. A detail description of one of the work holding and feeding mechanisms will therefore suffice for both.

The work holding table consists of a disk 70 35, the periphery of which is beveled at its under side and provided with teeth 36, to constitute a beveled gear and upon the upper face of this disk is fixed a stop 37 that has a clamping face conforming to the face of the 75 head of the violin through which opens the usual string or peg box. A movable clamping cam 38' is suitably pivoted upon the disk 35 in position to engage the opposite face of the head to be operated upon, when 80 the latter has been snugly fitted to the correspondingly shaped holder 37, the cam having an operating handle 39'. It will be understood however of course, that the blank may be held upon the disk shaped table 35 85 in any desired manner to position it with the axis of the ultimate scroll accurately aligned with the axis of the table.

The table disk 35 is provided with a stem 90 in the form of a stub shaft 38 that has a bearing in the horizontal arm 39 of a bracket or carrier member that includes also a vertical arm 40, the arm 39 having bosses 41 and 42 projecting from its upper and lower faces respectively and through which the said 95 bearing of the stub shaft 38 is continued to hold the shaft securely against chattering. The carrier member referred to, is supported in a second carrier member in the form of a bracket that includes a vertical 100 arm 43 and a horizontal arm that in turn includes the laterally spaced rails 44 that are connected slightly short of their free ends, by the cross member 45 from which depends a horizontal sleeve 46 that is internally threaded, for a purpose to be 105 presently explained. The arm 40 is passed downwardly between the guide rails 44 and the arm 39 rests upon the ledges 47 at the inner sides and at the bases of the guide 110 rails. The first named carrier member is thus supported by the second carrier member while having limited sliding movement thereon, for a purpose to be presently explained.

To mount the second named carrier member, that includes the arm 43, there extends from the standard 10 a bracket arm 48 having at its outer end a broadened guide plate 49 against which is disposed the arm 43 120 115 which is longitudinally channelled as shown at 50 to receive the portion 49, retainer plates 51 being fixed to the arm 43 and engaging behind the portion 49, where they are adjusted by their retaining screws 52 to 125 hold the arm 43 slidably but with sufficient snugness to prevent chattering.

The carrier member arm 40 has a boss 53 from which projects a stub shaft 54 on which is mounted a rotatable cam 55 that de- 130

termines the reciprocation of the work vertically during the cutting operation, in a manner to be presently explained, but this cam serves also as a member of the mechanism by which the work supporting table is initially elevated and finally lowered. This mechanism includes a block 56 that is channelled in its rear face, in the same manner as is the carrier member arm 43, to receive the lower portion of the guide plate 49 that depends from the bracket arm 48, the block being held slidably to the guide plate by the keeper strips 57 that are held adjustably by the screws 58. At the upper end of the block 56 is a stub shaft 59 on which is rotatably mounted a roller 60 on which the cam 55 rests. Now the arm 39 of the first named cam member, being confined slidably between the guide rails 44 by the keeper strips 61 that are screwed onto the upper faces of the guide rails, it will be understood that when the block 56 is raised and lowered, the work table carrying members, together with the table and associated parts, will be correspondingly moved.

To effect vertical reciprocation of the block 56, there is pivotally connected with its lower end portion a shift rod 62 that is passed downwardly and through a tube 63 that is exteriorly threaded and screwed through a sleeve 64 at the outer end of an arm 65 that radiates from the standard 10. Near the lower end of the rod 62 is a substantially hemispherical head 66 that rests in a socket in the upper face of a foot operated lever 67, the rod continuing through the bottom of the socket and into a guide opening 68 in the base 14 of the standard 10. The lever 67 has a spring 69 under its engaged end portion to hold it raised against the head 66, and its opposite end terminates in a pedal 70.

Upon the rod 62 and resting with its lower end against the head 66, is a helical spring 71, the upper end portion of which encircles the tube 63 and engages against a jam nut 72 on the tube in position to impinge against the lower end of the sleeve 64. The upper end portion of the tube 63 is formed angular as shown at 73 to receive a wrench for adjustment of it through the sleeve, the lower end of the tube constituting a stop against which the head 66 strikes to limit the upward movement of the rod and therewith the block 56 and the parts thereabove that are raised by it. It will of course be understood that by adjusting the tube 63 through the sleeve 64, the apparatus may be so set that when the pedal 70 is depressed, the work on the table will be raised to the exact position for the initial cutting operation of the corresponding cutter 21.

With a knowledge of the shape of a scroll end at the head of a violin, it will be understood that to form such a scroll end on a

blank presented to the cutter 21 upon the table 35, the work must be rotated and at the same time must be drawn laterally in a direction at right angles to the axis of the cutter to describe the expanding curve of the spiral, and must at the same time be reciprocated vertically to vary and even reverse the pitch of the scroll.

The mechanism for rotating the table 35 includes the gear teeth 36 at the periphery of the table and which engage the teeth of a beveled gear 75 that is carried by a shaft 76, the inner portion of which is threaded to form a screw that engages the nut or threaded sleeve 46 hereinbefore referred to, the shaft at its unthreaded portion between the threads and the gear wheel 75, having a bearing in a sleeve 77 that depends from the bracket arm 39, there being a collar 78 fixed upon the shaft by set screws 79 at the opposite side of the sleeve 77 from the gear wheel so that the shaft is held against movement longitudinally through the sleeve 77 while being free to rotate therein. Rotation of the shaft 76, which is accomplished by means of the crank 80, effects rotation of the table 35 through the gear 75 and teeth 36, at which time the shaft 38 of the table rotates in its bearing in the carrier arm 39. At the same time, the screw of the shaft 76 feeds out of the nut 46, and the collar 78 pressing against the sleeve 77, causes the carrier arm 39 to slide along the ledges 47 of the vertically shiftable carrier member and the table with its work to recede gradually and laterally from the cutter 21.

The spiral curve of the scroll end embodies a plurality of convolutions and while the blank or work is being given two complete rotations, it must, as before stated, be reciprocated vertically and variably, to produce the proper scroll pitch. This vertical shifting of the work during the cutting operation after the work table has been initially set, is accomplished through the medium of the cam disk 55, working on the friction roller abutment 60. The roller abutment 60 is of such length that the cam disk is in peripheral contact with it at all points of horizontal shift of the correspondingly movable carrier member.

To operate the cam 55, the intermeshing bevel gears 38' and 54' are provided that are fixed respectively to the lower end of the shaft 38 and the outer end of the hub of the cam 55, the gear 38' being one-half the diameter of the gear 54', so that while the table, and therewith the work is rotating twice, the cam will have one substantial rotation, which is its cycle of operation. The cam is shown in Figure 5 of the drawings, associated with the head having a scroll, the pitch of which has been governed by the cam and in the figure have been included lines leading from different portions of the

scroll face to the corresponding portions of the cam.

The cam, rests always on the roller 60 and at the beginning of the operation, the finger 5 81 that radiates from the cam, rests against one side of the roller 60. So long as the radius of the cam remains constant, there will of course be no vertical movement of the 10 table with the work thereon. When the radius increases, the cam of course becomes effective and by pressing on the roller 60 serves to slide the vertically shiftable carrier arm 43 upwardly on the guide plate 49, taking with it the laterally shiftable carrier 15 member, the table, the cooperating mechanism for rotating and shifting the table, and also the work on the table. The result is a corresponding pitch to the scroll. When that part of the scroll is reached where there 20 is no pitch, the radius of the cam continues constant for a corresponding angular distance, after which the radius gradually decreases to give the reverse pitch to the outer portion of the scroll where it merges into 25 the side wall or face of the string box. It will of course be understood that the cam may be modified to produce whatever pitch is desired and thus to shape the scroll accordingly, for while the apparatus is illustrated and described in connection with the manufacture of a musical instrument, the 30 illustration and description is only of that embodiment of the invention that it is elected to present in explanation of the invention 35 which is adapted for the working of materials for a variety of uses.

In practice, the apparatus has two attendants and after one scroll end has been formed at one side of the machine, the work 40 is passed to the other attendant, who reverses it and in the same manner as above described, forms the opposite scroll end. The single difference in the specific mechanisms at the opposite sides of the machine, being 45 that the screws of the shafts 76 are oppositely pitched so that the work is oppositely rotated as drawn laterally from the cutters.

It will be understood that the cutter 21 has 50 a breadth somewhat greater than the maximum breadth of the end face of the scroll and that this end face, when the work is taken from the machine, is at right angles to the axis of the scroll along all lines drawn 55 radially of the scroll. Lateral undulations or other modifications of the scroll face, are contributed subsequently.

What is claimed is:

1. A violin scroll forming machine comprising separate cutting faces arranged to cut in planes at an angle to each other, a work holder shiftable simultaneously in directions parallel with the cutting planes of both the cutting faces, and means for shifting 60 the work holder simultaneously in both

directions and with a predetermined and variable speed ratio.

2. A violin scroll forming machine comprising separate cutting faces arranged to cut in planes at an angle to each other, a work holder shiftable simultaneously in directions parallel with the cutting planes of both cutting faces, means for shifting the work holder simultaneously in both directions and with a predetermined and variable speed ratio, the work holder being rotatable in the plane of one of the planes in which it is shiftable.

3. A violin scroll forming machine comprising a rotatable cutter having a cutting face parallel with its axis of rotation and a cutting face at an angle thereto, a work holder, means for shifting the work holder in a direction parallel with one cutting face, and means operable from the first named means for variably shifting the work holder parallel with the other cutting face.

4. A violin scroll forming machine comprising a support, a rotatable cutter supported thereby and having a cutting face parallel with the axis of rotation of the cutter and a cutting face at an angle thereto, a carrier member connected with the support for movement parallel with the axis of rotation of the cutter, a second carrier mounted upon the first carrier and movable with respect thereto toward and away from the axis of rotation of the cutter, a rotatable work holder carried by the second carrier, means for shifting the first carrier, means for shifting the second carrier, and means for rotating the work holder, said means being operable one from the other.

5. A violin scroll forming machine comprising a support, a rotary cutter supported thereby, a carrier member connected with the support for movement toward and away from the cutter in directions parallel with the axis of rotation of the cutter, a second carrier mounted upon the first carrier and movable with respect thereto toward and away from the axis of rotation of the cutter, a rotary work holder carried by the second carrier, means for shifting the second carrier and means for shifting the first carrier, the last named shifting means including a governing element upon the second carrier that determines the working movement of the first carrier and is operably connected with the shifting means of the second carrier.

6. A violin scroll forming machine comprising a support, a rotary cutter supported thereby, a carrier member connected with the support for movement in directions parallel with the axis of rotation of the cutter, a second carrier mounted upon the first carrier and movable with respect thereto toward and away from the cutter, a work holder carried by the second carrier, and shiftable in a plane at an angle to the axis of rotation

- of the cutter, means for shifting the second carrier and means for initially shifting the first carrier, including a cam carried by and operable from the shifting means of the 5 second carrier and means against which the cam is operative for reciprocating the first named carrier, the carriers and work holder being mutually connected for movement one from another.
10. 7. A violin scroll forming machine comprising a support, a cutter supported thereby, a carrier member connected with the support for movement toward and away from the cutter in directions parallel with 15 the axis of rotation of the cutter, a cam carried by the carrier member, a rotary work holder carried by the carrier member and movable bodily therewith, an abutment against which the cam is operable to shift 20 the carrier upon operation of the cam and along which the cam is shiftable, and means for operating the cam, the abutment having means for shifting it to correspondingly move the carrier and therewith the work 25 holder with respect to the cutter.
8. A violin scroll forming machine comprising a support, a rotary cutter carried thereby, a carrier member connected with the support for movement toward and away 30 from the cutter in directions parallel with the axis of rotation of the cutter, a second carrier member carried by the first carrier member and movable thereon toward and away from the axis of the cutter, a rotary 35 work holder carried by the second carrier member, a cam carried by the second carrier member, an abutment against which the cam is operable to shift both carrier members with respect to the cutter and along which 40 abutment the cam is bodily shiftable, means operatively connected with the cam for moving the second carrier with respect to the first carrier, and means for shifting the abutment.
45. 9. A violin scroll forming machine comprising a rotary cutter having straight cutting faces at an angle to each other, a rotatable work holder and separate means operable one from the other for rotating the 50 work holder and for urging the holder in a plurality of straight directions respectively parallel with and at an angle to one of said cutting faces.
10. A violin scroll forming machine comprising a rotary cutter having a cutting face 55 parallel with its axis of rotation and a cutting face at an angle thereto, a work holder that is rotatable and shiftable parallel with both faces of the cutter, means for contributing 60 said movements to the holder and a single drive element for the contributing means.
11. A violin scroll forming machine comprising a rotary cutter having a cutting face 65 parallel with its axis of rotation and a cutting face at right angles thereto, a carrier shiftable parallel with one cutting face of the cutter, a second carrier shiftable on the first carrier parallel with the other cutting face of the cutter, a support for the first 70 carrier including a cam carried by the second carrier and an abutment shiftable toward and away from the cutter, and means connected with the cam and the second carrier for actuating the cam and shifting the second carrier with respect to the first carrier; the first carrier being shiftable toward and away from the cutter when the cam is actuated.
12. A violin scroll forming machine comprising a rotary cutter having a cutting face parallel with its axis of rotation and a cutting face at an angle thereto, a carrier shiftable, parallel with one face of the cutter, a second carrier shiftable on the first carrier 75 parallel with the other face of the cutter, a work holder carried by the second carrier and movable with respect thereto, a support for the first carrier including a shifting element and an element associated with the carriers 80 and through the medium of which the first carrier may be shifted upon shifting of the said shifting element, means for shifting the second carrier with respect to the first carrier and operatively connected with the said shifting element that is associated with the carriers and means for moving the work holder with respect to the second carrier, the work holder moving means and the shifting means of the second carrier having a 85 common drive element whereby movement of the carriers together, movement of the second carrier with respect to the first carrier and movement of the work holder is simultaneously effected in predetermined relation.
13. A violin scroll forming machine comprising a rotary cutter having a cutting face parallel with its axis of rotation and a cutting face at right angles thereto, a rotatable work holder that is movably in the direction of its axis of rotation parallel with one face of the cutter and is movable parallel with the other face of the cutter toward and away from the cutter, a driving 95 element and means operable from the driving element for simultaneously rotating the work holder and shifting it in both of said directions.
14. A violin scroll forming machine comprising a rotary cutter having a cutting face parallel with its axis of rotation and a cutting face at right angles thereto, a rotatable work holder that is movable in the direction of its axis of rotation toward and away 100 from the cutter parallel with the axis of rotation of the latter and is movable at an angle to said axis toward and away from the cutter, a driving element and means operable from the driving element for simul- 105
15. 11. A violin scroll forming machine comprising a rotary cutter having a cutting face parallel with its axis of rotation and a cutting face at right angles thereto, a carrier shiftable parallel with one cutting face of the cutter, a second carrier shiftable on the first carrier parallel with the other cutting face of the cutter, a support for the first 110 carrier including a cam carried by the second carrier and an abutment shiftable toward and away from the cutter, and means connected with the cam and the second carrier for actuating the cam and shifting the second carrier with respect to the first carrier; the first carrier being shiftable toward and away from the cutter when the cam is actuated.
16. A violin scroll forming machine comprising a rotary cutter having a cutting face parallel with its axis of rotation and a cutting face at an angle thereto, a carrier shiftable, parallel with one face of the cutter, a second carrier shiftable on the first carrier parallel with the other face of the cutter, a work holder carried by the second carrier and movable with respect thereto, a support for the first carrier including a shifting element and an element associated with the carriers 115 and through the medium of which the first carrier may be shifted upon shifting of the said shifting element, means for shifting the second carrier with respect to the first carrier and operatively connected with the said shifting element that is associated with the carriers and means for moving the work holder with respect to the second carrier, the work holder moving means and the shifting means of the second carrier having a common drive element whereby movement of the carriers together, movement of the second carrier with respect to the first carrier and movement of the work holder is simultaneously effected in predetermined relation.
17. A violin scroll forming machine comprising a rotary cutter having a cutting face parallel with its axis of rotation and a cutting face at right angles thereto, a rotatable work holder that is movably in the direction of its axis of rotation parallel with one face of the cutter and is movable parallel with the other face of the cutter toward and away from the cutter, a driving 120 element and means operable from the driving element for simultaneously rotating the work holder and shifting it in both of said directions.
18. A violin scroll forming machine comprising a rotary cutter having a cutting face parallel with its axis of rotation and a cutting face at right angles thereto, a rotatable work holder that is movable in the direction of its axis of rotation toward and away 125 from the cutter parallel with the axis of rotation of the latter and is movable at an angle to said axis toward and away from the cutter, a driving element and means operable from the driving element for simul- 130

- 1 taneously rotating the work holder and for shifting it both in the direction of its axis of rotation variably and at an angle to said axis constantly.
- 5 15. A machine for cutting a scroll of variable pitch comprising a rotatable cylindrical cutter having an end cutting face and a side cutting face, a work holder that is rotatable and shiftable toward and away from the
- 10 cutter in the direction of its axis of rotation and at an angle to said axis, and means including a common driving element, for ro-

tating the work holder, for drawing it away from the cutter at an angle to its axis of rotation and for drawing it reciprocatingly 15 away from the cutter in a direction parallel to its axis of rotation.

In testimony whereof, I affix my signature, in the presence of two witnesses.

NICHOLAS P. PERKINS.
